UNITED STATES PATENT OFFICE.

CHARLIE J. ANDERSON AND GEORGE EVERSON, OF DETROIT, MICHIGAN.

MACHINE FOR DIPPING MATCHES.

SPECIFICATION forming part of Letters Patent No. 660,087, dated October 23, 1900.

Application filed July 11, 1900. Serial No. 23,205. (No model.)

To all whom it may concern:

Be it known that we, CHARLIE J. ANDERSON and GEORGE EVERSON, citizens of the United States of America, and residents of Detroit, in the county of Wayne and State of Michigan, have invented certain new and useful Improvements in Machines for Dipping Matches, of which the following is a specification, reference being had therein to the accompanying drawings.

This invention relates to machines for dipping matches—that is, for applying the paraffin and the igniting composition to the match-splints without the intervention of hand-labor.

The class of machines to which our invention more particularly relates is those in which the splints are cut from blocks of wood and clamped in frames, and these "dipping-frames," as they are called, are used as vehicles for conveying the splints from one part to another and holding the same while they are being dipped in the paraffin or similar inflammable coating and the fulminating or igniting composition.

Our invention is designed to facilitate the handling of the dipping-frames in the application to the splints of the paraffin and the igniting or fulminating composition; and to this end our invention consists of a suitable supporting-frame, in the initial portion of which is a reciprocating platen adapted to equalize the projecting ends of the splints contained in the frames, a heating box or chamber for said splints adjacent thereto, a paraffin-tank, a rotary brush for removing any loose or broken splints and next to that the tank and rolls for applying the igniting or fulminating composition, and means for drawing and guiding the frames past each of these various devices to be operated upon and delivering the same at a distance therefrom without the employment of hand-labor.

The invention further consists in the construction, arrangement, and combination of the various parts, all as more fully herein-after described, and shown in the accompanying drawings, in which—

Figures 1 and 2 are side elevations of a complete machine, showing the left and right hand ends of the machine, respectively. Fig. 3 is an end elevation of Fig. 1 looking from

the right. Fig. 4 is a side elevation of the equalizing-press for the match-splints. Fig. 5 is an end elevation thereof. Figs. 6 and 7 are elevations of the segmental gears for intermittently operating said press and feed-chains. Fig. 8 is a perspective view of one of the chain-links and cross-bar.

In the drawings, A is the supporting-frame, composed of the uprights 1, 2, 3, 4, 5, 6, and 7, united at their tops by the connecting-pieces 8, the uprights 2, 3, 5, and 6 being double the height of the other uprights and having an additional connecting-piece 9 at their middle.

10 are brackets adjustably sleeved on the uprights, and supported on these brackets are the L-shaped guide-rails 11, extending the entire length of the frame, on each side thereof, thus forming a continuous track for supporting the dipping-frames throughout the entire length of the machine.

On the initial portion of this machine or table are a pair of intermittently-operated 75 endless sprocket-chains 12, passing over the sprocket-wheels 13 14 on the shafts 15 16, journaled in suitable bearings sleeved on the uprights 1 and 2, these sprocket-wheels being so arranged that the upper portion of the 80 sprocket-chains will be substantially in line with the guide-rails and adjacent thereto.

Above the sprocket-wheels 13 and substantially in line with the upper edge of the guide-rail are a second pair of continuously-moving 85 endless carrier-chains 17, which are of a length equal to the remaining portion of the feed table or frame and which in their return movement pass over the idler-wheels 18, 19, 20, 22, 23, and 24, mounted on the shafts 25, 90 26, 27, 30, 31, and 32, adjustably secured in suitable bearings sleeved on the uprights 2, 3, 5, and 6.

The continuously-moving carrier-chains 17 overlap the intermittently-operated chains 12 95 slightly and are arranged above the same a distance equal to the height of a dipping-frame, so that a frame in passing from one set of carriers to the other will have to pass between the two. Both sets of carriers 12 and 100 17 are driven from the same common shaft, the chains 17 being continuously driven, while the chains 12 are intermittently driven through intermediate gearing at twice the

speed of the chains 17, so that the capacity of the two chains is exactly alike, and by reason of being driven from the same common shaft the relative speed of the chains can be 5 so timed that all danger of the cross-bars interfering with the top of the frames is avoided.

Spaced along the outer surface of each pair of chains at suitable intervals are a series of angular cross-bars 36, which are connected at 10 their opposite ends to the carrier-chains, said cross-bars being adapted to engage with the rear face of the dipping-frame, and thus slide the same along the guideways past the various devices. The construction and manner 15 of attaching these bars are fully shown in Fig. 8, in which 34 is a link provided with the lug 35, to which the cross-bar 36 is secured. We may provide an additional lug 38 on the opposite side of the link, as shown in dotted lines, 20 to ride on the guide-rail, and thus prevent the chain from sagging.

B is a reciprocating butter or equalizing-press mounted upon a suitable base and across the bed-plate of which are secured the 25 guide-rails 11, the upper part of the carrier-chains 12 also traveling across said bed-plate.

B' B' are uprights secured upon the bed-plate B², forming vertical guides in which the reciprocating platen B³ travels, said platen 30 being driven from an eccentric B⁴, mounted upon the transverse shaft B⁵, journaled in suitable bearings on the uprights and carrying the pinion B⁶, meshing with a segmental gear on the driven shaft adapted to transmit motion intermittently thereto, or other 35 equivalent mechanism may be employed. C is a transverse shaft mounted in bearings near the base of said uprights, carrying the pinion C' and sprocket-wheel C², said pinion meshing with a segmental gear on the drive-shaft 40 adapted to transmit motion intermittently thereto, and C³ is a drive-chain connecting the sprocket C² with a sprocket-wheel on shaft 45 16, thus imparting an intermittent motion to the endless carrier-chains 12.

D is a drive-shaft mounted in bearings intermediate the shafts B⁵ and C and carrying at one end the tight and loose pulleys D' D² and the segmental gear D³, adapted to mesh 50 with the pinion C', and at its opposite end the segmental gear D⁴, meshing with the pinion B⁶. D⁵ is a drive-sprocket on said shaft adapted to transmit motion to the endless carrier-chains 17 17 through the medium of 55 the drive-chain D⁶, passing over a suitable sprocket-wheel on the shaft 31, carrying the drive-sprockets 23. It will thus be seen that as motion is imparted to the drive-shaft D the segmental gears D³ and D⁴, meshing with 60 the pinions C' and B⁶, will cause the shafts B⁵ and C to revolve, the shaft C remaining stationary while the eccentric on the shaft B⁵ reciprocates the platen and the shaft B⁵ remaining stationary while the shaft C makes 65 one complete revolution, which through the medium of intermediate drive connections causes the intermittent carrier-chains 12 to

place a newly-filled frame under the platen and move the other forward. It will be seen from the drawings that the relation between 70 the gears D³ D⁴ and pinions C' and B⁶ is one to two and one to four, respectively, so that the platen will reciprocate with a quarter-revolution of the shaft D and remain idle during the balance of the revolution, and the shaft C, with but a half-revolution of the shaft D, will make a complete revolution and remain idle during the balance of the revolution, thus causing the carrier-chains 12 to move at twice the speed of the continuously-driven chains 17 and to remain stationary one-half of the time—that is, while under the platen. The construction of the gears by means of which we are enabled to obtain this intermittent movement of the platen and carrier-chains 12 is fully shown in Figs. 6 and 7.

After the matches have been equalized in the dipping-frames by means of the reciprocating platen they are slid from underneath the platen along the guide-rails by reason of 90 the intermittently-operated chains being set in motion until one of the angular cross-bars on the continuously-moving carrier-chains 17 engages with the rear edge of the frame and slides it along over the heater E, which is provided 95 with any suitable source of heat, and thence to the paraffin-tank F, which is mounted upon a suitable base and has a double bottom, so that the steam may be constantly supplied to keep the paraffin in a liquid state, a suitable 100 faucet being provided so that the paraffin may be drawn off. Suspended above the paraffin-tank proper is the paraffin-supply tank H, which is provided with a suitable steam-coil within, so that the cakes of paraffin may be 105 melted therein and a supply constantly kept on hand, a suitable faucet being provided so that the paraffin in the tank proper can be replenished when necessary.

The guide-rails 11 are made with a double 110 incline J when passing over the paraffin-tank, so that the lower ends of the matches contained in the dipping-frame will be dipped into the paraffin, suitable antifriction-wheels K being provided to cause the carrier-chains 115 to descend with the frame.

After the matches have been paraffined they are fed along the table a short distance (so that the paraffin may harden) to a rotary brush L, driven by means of the carrier-chains 17, passing over the sprocket-wheels L' on the shaft L², which carries a gear L³, meshing with gear L⁴ on the shaft carrying said brush, which removes any broken or loose splints that may have become wedged 125 between the matches secured in the frame. Otherwise these loose or broken splints would adhere to the composition-roll, and thus destroy its uniform working. From the rotary brush the dipping-frames are slid along the 130 guideways and passed between the composition-rollers M N and the igniting or fulminating composition added to the tip of the match by the roll N revolving in a tank N',

containing the composition, said tank being mounted upon a suitable base and having a steam or hot-water jacket N^2 surrounding said tank to keep the composition at a proper consistency. The composition-rolls are revolved by means of the carrier-chains passing around the sprockets O on the shaft O' , journaled in suitable bearings on the uprights S and carrying the drive-gear O^2 , meshing with gear O^3 on the shaft of the upper composition-roll, which in turn carries a gear O^4 , which meshes with a gear O^5 on the lower roll, the composition-rolls being turned at a sufficiently slow speed to effectually head the matches. After passing through the composition-rolls the frames are run along the guideways a short distance and delivered to the unloading-machines for further manipulation, the endless sprocket-chains returning by means of the idler-wheels overhead, and thus forming the driving means for the composition-rolls and rotary brush in their return movement, as already described.

It will thus be seen that our machine is of simple construction, compact, and does away entirely with the repeated handling of the dipping-frames, which is a great item in the cost of manufacture of matches, besides greatly increasing the capacity of the plant.

It is within the spirit of our invention to use any approved form of endless chains, equalizer, heating apparatus, paraffin-pan, rotary brush, or composition-applying means, also any driving means which would accomplish the result described.

What we claim as our invention is—

1. In a machine for dipping matches, two sets of endless-chain carriers coöperating with each other to carry the dipping-frames in combination with guides in which said dipping-frames are supported, one of the carriers having an intermittent motion and operating below the guides and the other having a continuous motion and operating above the guides substantially as set forth.

2. In a machine for dipping matches, two sets of endless-chain carriers coöperating with each other to carry the dipping-frames in combination with the guides in which said dipping-frames are supported, one of the carriers having an intermittent motion and operating below the guides and the other having a continuous motion and operating above the guides and a reciprocating platen operating in the path of the intermittently-moving carrier-chains and in unison therewith substantially as described.

3. In a machine for dipping matches, two sets of endless-chain carriers coöperating with each other to carry the dipping-frames in combination with the guides in which said dipping-frames are supported, one of the carriers having an intermittent motion and operating below the guides and the other having a continuous motion and operating above the guides and the equalizing device B having

the fixed platen B^2 in the bed of the intermittently-operated carrier-chains on which the match-frames are supported and the intermittently-reciprocating platen B^3 above it co-operating with the carrier. 70

4. In a machine for dipping matches the combination with a supporting-frame provided with guide-rails throughout its entire length, of two sets of endless carrier-chains 75 driven from the same common shaft, comprising an intermittently-operated pair of chains traveling in line with the lower edge of the guide-rails and a continuously-operated pair of chains coöperating therewith and traveling in line with the upper edge of the guide-rails, cross-bars 36 spaced at suitable intervals along said chains and adapted to slide the dipping-frames along the guide-rails substantially as set forth. 85

5. A machine for dipping matches, comprising essentially a frame provided with guide-rails throughout its entire length, two sets of endless drag-chains traveling in line with said rails and adjacent thereto, both sets being driven from the same common shaft one set traveling in line with the lower edge of the guide-rails and being intermittently driven and the other set traveling in line with the upper edge of the guide-rails and being continuously driven both sets coöperating with each other to slide the dipping-frames along the guide-rails, a reciprocating platen in the path of the intermittently-operated carrier and operating in conjunction therewith, a rotary brush in the path of the continuously-operated carrier and means for applying the igniting and fulminating composition to the splints. 95

6. In a machine for dipping matches, the combination with the frame and the guide-rails, of the endless carrier-belts 12 and 17 , coöperating with each other, the cross-bars 36 spaced at intervals along said carriers and adapted to engage with the rear edge of the dipping-frame and slide the same along the guide-rails, the equalizer B located in the path of the carriers 12 and carrying the drive-shaft, the transverse shafts B^5 , C carrying pinions adapted to mesh with segmental gears on the drive-shaft and thereby impart an intermittent motion to the reciprocating platen and carrier-chains 12 respectively and means for driving the carriers 17 continuously from said drive-shaft. 110 115 120

7. In a machine for dipping matches, the equalizer B supported upon a suitable base to which the vertical uprights or guides B' are secured, the platen B^3 reciprocating in said guides, the drive-shaft D mounted in bearings on said uprights and carrying the loose and tight pulleys D' , D^2 and segmental gears D^3 at one end and the segmental gear D^4 and sprocket-wheel D^5 on the other end, the horizontal shafts B^5 and C mounted in bearings on said uprights parallel with the drive-shaft and carrying the pinions C' and 125 130

B^6 meshing with said gears respectively and adapted to drive the chains 12 and platen B^3 intermittently to coöperate with each other.

8. In a machine for dipping matches, two sets of endless drag-chains 12 and 17 coöperating with each other and united at intervals by cross-bars, an evener in the path of one of the chains, a rotary brush L and composition-rollers M, N, in the path of the other

pair of chains all coöperating with each other to and driven from the same common shaft.

In testimony whereof we affix our signatures in presence of two witnesses.

CHARLIE J. ANDERSON.
GEORGE EVERSON.
